UNITED STATES PATENT OFFICE.

CHARLES F. BALDWIN, OF MONTCLAIR, NEW JERSEY, ASSIGNOR, BY MESNE ASSIGNMENTS, TO WESTERN ELECTRIC COMPANY, INCORPORATED, A CORPORATION OF NEW YORK.

TERMINAL BANK.

1,178,207.

Specification of Letters Patent. Patented Apr. 4, 1916.

Application filed July 6, 1914. Serial No. 849,344.

To all whom it may concern:

Be it known that I, CHARLES F. BALDWIN, a citizen of the United States, residing at Montclair, in the county of Essex and State of New Jersey, have invented certain new and useful Improvements in Terminal Banks, of which the following is a full, clear, concise, and exact description.

This invention relates to terminal banks particularly adapted for use in building up contact banks for automatic telephone exchange switchboards, although obviously suitable for many other uses. Its principal object is to provide an improved bank of the above type, wherein the terminals are uniformly and properly spaced and the tendency to sag, separate and warp is practically nil. To this end a structure is formed of superposed metal terminal strips and insulating compound coated paper, the paper without compound being of a thickness greater than the distance between adjacent terminal strips of the finished product; pressure then serving to effect a uniform spacing, expel all superfluous compound and compress the paper until its thickness, plus whatever compound remains between layers of paper and metal, equals the required distance between adjacent terminal strips.

The above and other objects of this invention will be fully set forth in the following description and claims, and will be more readily understood by reference to the accompanying drawing, in which—

Figure 1 is an enlarged view of a section of the coated paper; Fig. 2 is an elevation of a section of a terminal bank before the application of pressure; Fig. 3 illustrates the condition of the structure of Fig. 2 after compression; Fig. 4 shows the relative thickness of the coated paper before and after compression; Fig. 5 is an elevation of a built-up contact bank; and Fig. 6 shows in detail a particularly suitable form of metal terminal strip.

It has been found that terminal banks, built up in the usual way, of superimposed layers of plastic insulation coated paper sheets and metal terminal strips are liable to deteriorate and their usefulness become seriously impaired after a time, due to the settling, warping and separating of the various layers. This tendency is particularly noticeable at or near the top of the banks, and is found to some extent even when the

structure has been formed by the application of pressure sufficient to give a uniform spacing of the terminals and the proper overall dimensions. It is believed that this tendency is due to the "cold flow" of the insulating compound covering the paper. In other words, it is due to the ability of a compound plastic above ordinary temperatures but practically solid at ordinary temperatures, to creep or slowly change its position at ordinary temperatures. The terminal bank of this invention is practically free from these objections, which makes it a highly satisfactory structure, particularly from the standpoint of maintenance.

The structure is composed of superimposed layers of insulation coated paper 5 and metal terminal strips 6. The insulation coating on the paper sheets is a composition which is, or may become, plastic at temperatures above ordinary temperatures, so that all the surplus may be readily squeezed out from between the paper and metal strips and all the fissures and crevices in the paper filled therewith. The paper without insulation is of a thickness considerably in excess of the distance between the terminal strips of the finished bank, and is of a comparatively spongy or porous nature, so that when the proper amount of pressure is applied the terminals will be properly and uniformly spaced, and the paper therebetween will be so compressed that its thickness plus the films of compound yet remaining will make up the distance between adjacent terminal strips. This change in cross-section is plainly shown in Figs. 2, 3 and 4. The banks thus made up may be individually held together and supported by clamping bars 10 and holding screws 11, or several may be piled up and collectively held by the clamping members 10 and 11.

A particularly suitable form of metal terminal strip is shown in Fig. 6. This detail may be readily stamped by a punch press, projections 15 serving as terminals to be engaged by movable brushes or other contact members of the switchboard. The connecting wires may be readily attached by furnishing suitable lateral extensions 16. The terminal strips are provided with openings 17, through which holding or centering screws, such as 18, may pass. They also serve to reduce the body of metal, resulting in a lowering of the electrostatic capacity.

The invention claimed is:

1. A terminal bank comprising superimposed, compressed and substantially uniformly-spaced layers of insulation coated paper, and metal terminal strips, the distance between adjacent terminal strips after compression being less than the thickness of the paper, minus its coating, before compression.
2. The process of forming a terminal bank, which consists in superposing layers

of insulation coated paper and metal terminal strips, and compressing the bank thus formed until the paper is less than its original thickness.

15

In witness whereof, I hereunto subscribe my name this 1st day of July A. D., 1914.

CHARLES F. BALDWIN.
